UNITED STATES PATENT OFFICE.

WILLIAM E. ROUNSEVILLE, OF ATTLEBORO, MASSACHUSETTS, ASSIGNOR TO C. A. MARSH AND COMPANY, OF ATTLEBORO, MASSACHUSETTS, A FIRM.

DESIGN FOR A BELT-CLASP.

55,082.

Specification for Design.

Patented May 4, 1920.

Application filed February 24, 1920. Serial No. 360,991. Term of patent 7 years.

To all whom it may concern:

Be it known that I, WILLIAM E. ROUNSEVILLE, a citizen of the United States, residing at Attleboro, in the county of Bristol and State of Massachusetts, have invented a certain new, original, and ornamental Design for a Belt-Clasp, of which the following is a specification, reference being had to the accompanying drawings, forming a part thereof, wherein,

Figure 1 is a front elevation of a belt clasp embodying my new design, and

Fig. 2, an end elevation of the same.

A feature of this design is the combination with a transversely and longitudinally swelled oblong body, producing a shaded belly contour, of a surrounding bevel shaped border.

I claim:

The ornamental design for a belt clasp, as shown.

WILLIAM E. ROUNSEVILLE.
